UNITED STATES PATENT OFFICE

CLARENCE D. MAURER, OF WEST READING, PENNSYLVANIA, ASSIGNOR TO NARROW FABRIC COMPANY, OF WEST READING, PENNSYLVANIA, A CORPORATION OF PENNSYLVANIA

DESIGN FOR AN ELASTIC LACE BRAID

Application filed April 28, 1932. Serial No. 43,646. Term of patent 14 years.

To all whom it may concern:

Be it known that I, CLARENCE D. MAURER, a citizen of the United States of America, residing at West Reading, in the county of Berks and State of Pennsylvania, have invented a new, original, and ornamental Design for an Elastic Lace Braid, of which the following is a specification, reference being had to the accompanying drawing, forming part thereof.

The drawing is an enlarged plan view of an

elastic lace braid embodying my ornamental design. The braid is shown enlarged approximately 1½ times actual size, but which in the reduction to patent size will show the braid approximately actual size.

I claim:

The ornamental design for an elastic lace braid, as shown and described.

In testimony whereof I affix my signature.

CLARENCE D. MAURER.
